RAILWAY TRANSIT CAR BODY

William M. Schmidt, Harper Woods, Mich., assignor to
Pullman Incorporated, Chicago, Ill., a corporation of
Delaware

Filed June 28, 1967, Ser. No. 7,633

Term of patent 14 years

(Cl. D66—1)

FIG. 1 is a perspective view of a railway transit car body showing my new design; and

FIG. 2 is a front end elevational view thereof.

The essential features of my design reside in the portion shown in full lines.

I claim:

The ornamental design for a railway transit car body, substantially as shown and described.
